(57) **CLAIM**

The ornamental design for an automobile, toy replica and/or other replicas, as shown and described.

DESCRIPTION

FIG. 1 is a perspective view from the front left side of a first embodiment of an automobile, toy replica and/or other replicas.

FIG. 2 is a perspective view from the rear left side thereof.

FIG. 3 is a left side elevation view thereof.

FIG. 4 is a right side elevation view thereof.

FIG. 5 is a front elevation view thereof.

FIG. 6 is a rear elevation view thereof; and,

FIG. 7 is a top plan view thereof.

The portions of the article shown in broken lines are for the purpose of showing environmental structure only and form no part of the claimed design. The dot-dash lines show an unclaimed boundary which forms no part of the claimed design.
